TAXICAB

Lynn Brodton, Trenton, N. J.

Application February 23, 1954, Serial No. 29,182

Term of patent 14 years

(Cl. D14—3)

To all whom it may concern:

Be it known that I, Lynn Brodton, have invented a new, original, and ornamental Design for Taxicab, of which the following is a specification, reference being had to the accompanying drawing, forming a part hereof, wherein:

Fig. 1 is a front perspective view of the taxicab of my design; and

Fig. 2 is a rear perspective view thereof.

The characteristic features of my design reside in the portions shown by means of full lines in the drawing.

I claim:

The ornamental design for a taxicab, substantially as shown and described.
